CLAIM

I claim the ornamental design for a shooting target, as shown and described.

DESCRIPTION

FIG. 1 is a perspective view of a shooting target, showing my new design in a tripped position;

FIG. 2 is an enlarged perspective view thereof;

FIG. 3 is a front elevational view of FIG. 2, the rear elevational view being a mirror image thereof;

FIG. 4 is a right-side elevational view of FIG. 2, the left-side elevational view being a mirror image thereof;

FIG. 5 is a top plan view of FIG. 2;

FIG. 6 is a bottom plan view of FIG. 2;

FIG. 7 is a perspective view thereof, showing the shooting target in a set position; and,

FIG. 8 is a front elevational view of FIG. 7, the rear elevational view being a mirror image thereof.

The broken lines showing additional shooting targets in FIG. 1 depict environmental matter and form no part of the claimed design.
